UNITED STATES PATENT OFFICE

2,576,843

HEAT EXCHANGE APPARATUS

Carl Johan Lockman, Stockholm, Sweden, assignor to Aktiebolaget Rosenblads Patenter, Stockholm, Sweden

Application April 20, 1948, Serial No. 22,215
In Sweden December 30, 1944

4 Claims. (Cl. 257—1)

1

The present invention relates to heat exchange apparatus of the surface type for heating, evaporating and like purposes and to a method of operating the same.

More particularly the invention is concerned with such apparatus as serving for transmitting heat from vapours to a scale forming liquid, and in which the paths of the different fluids may be interchanged at intervals during operation in order that any scale formed by the liquid on the walls of either fluid passage during one period should be substantially removed by the dissolving action of the vapours and their condensate when passed through the same passage during a following period.

The indicated method of removing scale by passing each of the fluids alternately through another one of the fluid passages is obviously a very desirable one since it may be performed practically without stopping operation and the change may be made at shorter or longer intervals as may be desired in any given case without unfavorably influencing either the continuance of operation or the costs, so that the cleaning may be timed to commence when the scale deposits are still very moderate and relatively easy to dissolve.

However, the cleaning capacity of the vapours more or less depends upon and is limited by certain factors of which one of great importance is that they produce a sufficient volume of condensate relative to the surfaces of the walls of the passage to provide continuous and ample wetting of all of the surface of the latter by an evenly distributed flow of liquid condensate, since it is a liquid condensate that provides the most active dissolving agent.

In practice the ideal conditions cannot be secured without special arrangements for the obvious reason, for instance, that the deposition of condensate will be only very slight adjacent to the place where the vapours enter and still less of the condensate will immediately be distributed upon the wall surfaces in that region and possibly only over parts thereof, whereas the flow of condensate will increase more and more towards the opposite end of the vapour passage. Consequently, in case of relatively resistant scale deposits the cleaning action may be quite inadequate near the entrance end while more or less adequate in the central region and rather satisfactory at the opposite end. With such operation, however, the practical value of the method is doubtful or to a great extent reduced because then the incompletely removed portions of scale

2

deposits will increase continually and sooner or later make it necessary to take the apparatus out of operation for a more thorough cleaning by chemical or mechanical means and this will involve excessive costs.

It is an object of the invention to provide means for circulating condensate through the passages which are used intermittently as vapour passages to secure a satisfactory and more even flow of condensate over the passage walls in order to increase the cleaning capacity and eliminate the drawbacks mentioned.

Another object of the invention is to provide means for distributing circulated condensate in a sub-divided state as by spraying nozzles, for instance, in order to further facilitate wetting of the passage walls and increase the cleaning efficiency.

A further object of the invention is to use the heating vapours in a jet condenser for circulating and distributing condensate as desired.

A still further object of the invention is to cause circulation of condensate as indicated in quantities which exceed the quantity formed by condensation and preferably amount to a plurality of times the amount of the condensate.

Still further objects will be apparent from the following.

Suitable embodiments of the invention will now be described with reference to the accompanying drawings, in which:

Figure 1 shows a plant with a heat exchanger having a pump for circulating condensate.

Figure 1a shows another arrangement employing an injector instead of a pump.

Figure 2 is a section of the same exchanger shown in Figures 1 and 1a with inlets and outlets for the two heat exchanging fluids, taken along the line II—II in Figure 1.

Figure 3 is a section of the heat exchanger taken along the line III—III in Figure 1, and

Figure 4 is a section of the heat exchanger taken along the line IV—IV in Figure 1.

In all figures the same reference characters refer to the same parts.

The heat exchanger 1 comprises a plurality of parallel heat transmitting walls 2 of sheet metal spaced at equal distances between two side plates 3. Together with the plates 3 and strips 4 the walls 2 form a system of equally shaped parallel and vertical channels 12 and 12a. Above and beneath the ends of the strips 4 the walls 2 are extended in a V-shaped configuration so that at the top and the bottom the walls terminate in oblique edges 5, 5a, 5b and 5c respectively. Each

channel is closed along one of its oblique bottom edges, for instance the left one 5a, by means of a strip 6a, and in the same manner, the same channel is closed along one of its top edges, for instance likewise the left one, 5c by means of a strip 6b, although, instead, the right top edge 5b may be closed if desired. The adjacent channels 12a are closed along the remaining bottom and top edges 5, 5b respectively. In this manner alternate channels will be open to alternate sides, and there are thus formed two groups of channels, one group being open to one side, for instance the left one, and the other group being open to the other side, for instance the right one. Covers 1, at both sides closed by the extended side plates 3, enclose chambers 8, 8a, 8b, 8c, at the bottom and the top of the channels 12, 12a. The left-hand chambers 8a, 8c connect the channels 12a of the group open to the left while the right-hand chambers 8, 8b connect the channels 12 of the group open to the right. It is also clearly seen that the right-hand bottom chamber 8 communicates with the right-hand top chamber 8b through the channels 12 and that the left-hand bottom chamber 8a communicates with the left-hand top chamber 8c through the channels 12a.

The scale forming liquid to be heated may be introduced into the exchanger through a conduit 9, a valve 10 and an intake 11 and then passes through the channels 12 whereupon it is withdrawn through the outlet 13, a valve 14 and a conduit 15. In the embodiment shown in Figure 1, a vaporous heating medium may be introduced through a valve 16, conduit 18, a valve 19a (Fig. 2) and an intake 13a into the channels 12a. From the channels 12a condensate may be withdrawn through the outlet 11a, a valve 23a, and conduit 20, a float chamber or vessel 21, a conduit 22, a pump 24 (Fig. 1), conduits 25, 26 and a discharge conduit 26a controlled by a throttle valve 27. The valve 27 is operated from the float 28 by means of a link system 29 so that the valve 21 will close when the level of the condensate in the vessel 21 sinks while the valve will open when the said condensate level rises.

Alternately, the paths of flow of the heated and heating media passing through the heat exchanger may be interchanged so that the liquid will be introduced to the channels 12a through the valve 10a and withdrawn from said channels through the intake 13a and valve 14a, while the vaporous heating medium will be introduced into the channels 12 through the valve 19 and inlet 13, the condensate formed being withdrawn through the valve 23. Interchanging of the passages may be effected periodically so that channels which are conveying liquid during a given period will be conveying vapour during the next period.

Condensate withdrawn from the heat exchanger is passed in circulation through the pump 24, conduits 21, 32 and valve 33 or through conduit 32a and valve 33a into a condensate distributing pipe 34 or 34a, respectively. During this cycle of operation the valve 39 in the conduit 28 above the conduits 32, 32a is closed. The valves 33, 33a are set so as to supply the condensate to that one of the pipes 34, 34a which is arranged in the top chamber 8a or 8c conveying the heating medium. The condensate distributing pipes are closed at their ends 35 and 35a, respectively, and provided with a number of nozzles 36 adapted to spread the condensate over the whole top of the heating surfaces of the chan-

nels. Thus, during a given period condensate will be flooded over said surfaces of the channels 12 conveying the heating medium, so as to remove scale therefrom precipitated from the liquid during the preceding period when said channels were conveying liquid. Owing to the fact that the channels are directed vertically and their heating surfaces likewise are vertical and since the heating surfaces have a substantially uniform width from the top to the bottom, the condensate distributed over the top part of the surfaces will continue to flood all remaining parts of the heating surfaces while flowing downward, so that the whole surfaces will be cleaned completely and very effectively.

Alternatively, as shown in Figure 1a, the vaporous heating medium may be introduced into the system through the valve 16 and an injector 38 communicating with the conduit 18 so as to effect the circulation of the condensate by means of the suction action of the vapour. In this manner the condensate will be supplied to the heat exchanger through the conduit 25, valve 39 and conduit 18 intimately mixed with the vapour. In this case the injector will serve both as circulating pump and as condensate distributing means so that the pump and distributing device may be omitted if desired.

In some cases it may be of advantage to circulate a quantity of condensate exceeding the quantity formed by new condensation in the heat exchanger. Thus, in starting the operation of the heat exchanger the condensate will be circulated and withdrawal of condensate will occur automatically as soon as the total quantity of the condensate is sufficient for causing the float 28 to open the valve 27.

Within the scope of the invention there can naturally be made further changes and modifications in its application in addition to those illustrated or described above. For instance, different pairs of branch valves for changing the flow paths of the fluids may be replaced by three-way valves or the main return pipe for condensate may terminate in the main supply pipe for heating steam. Of course the heat exchanger may be of any suitable construction but obviously it is preferred to use a laminated type or such a one in which the different fluid passages may be made substantially uniform in shape with fairly equal proportions.

Thus, it is understood that the invention is not limited otherwise than by the appended claims.

What I claim and desire to secure by Letters Patent is:

1. In a heat exchange apparatus having passages for conducting a heating medium and a scale forming liquid in heat exchange relation, said passages being formed between substantially equally spaced and parallel plate partition walls and each of the passages being open at the top and bottom, a valved inlet connection for conducting said heating medium to alternate passages, a valved outlet connection for discharging condensate from said heating medium from said passages, a valved inlet connection for conducting said scale forming liquid to the remaining passages, a valved outlet connection for conducting said liquid from said passages, valve means for interchanging the paths of flow of said heating medium and said liquid, a collecting device for receiving condensate discharged from said passages, a valved outlet connection from said collecting device, valved connections from said outlet connection to the open

top ends of said passages, and means for selectively circulating condensate through said last named connections and discharging the circulated condensate in subdivided and distributed form on the topmost parts of the walls of said passages to remove scale deposits therefrom.

2. In a heat exchange apparatus as described in claim 1, a valved drainage connection disposed in the outlet connection of the collecting device, means responsive to the level of condensate in said collecting device for automatically controlling the operation of said valved connection for withdrawing new amounts of condensate formed in the apparatus, and a circulating pump for circulating condensate from the collecting device into the topmost part of said passages.

3. In a heat exchange apparatus having passages for conducting a heating medium and a scale forming liquid in heat exchange relation, said passages being formed between substantially equally spaced and parallel vertical partitions and each passage being open at the top and the bottom, a valved inlet connection for conducting said heating medium to the open top ends of alternate passages, a valved outlet connection for discharging condensate from said heating medium from said passages, a valved inlet connection for conducting said scale forming liquid to the inlets of the remaining passages, a valved outlet connection for conducting said liquid from said passages, valve means for interchanging the paths of flow of said medium and said liquid, a collecting device for receiving condensate discharged from said passages, a valved outlet connection from said collecting de- 35

vice, valved connections from said outlet connection to the open top ends of said passages, an injector associated with said last named valved connections, and means for conducting vaporous heating medium through said injector for selectively circulating condensate from said draining device to the heating medium supplied to said passages whereby condensate is distributed on the walls of said passages in a subdivided state to remove scale deposits therefrom.

4. A heat exchange apparatus as described in claim 3 in which the injector is positioned substantially adjacent the inlet connections to the passages in the heat exchanger whereby a mixture of condensate and heating medium will be sprayed directly upon the walls of said passages.
